(57) **CLAIM**

The ornamental design for a one-piece crimper housing, as shown and described.

DESCRIPTION

FIG. 1 is a front, elevation view of a one-piece crimper housing embodying our new design.

FIG. 2 is a rear elevational view.

FIG. 3 is a left elevational view.

FIG. 4 is a right elevational view.

FIG. 5 is a top plan view.

FIG. 6 is a bottom plan view; and,

FIG. 7 is a front perspective view.

The broken lines shown in FIGS. 1, 2, and 7 are for illustrative purposes only and form no part of the claimed design.
